UNITED STATES PATENT OFFICE.

WILLIAM S. SOLOMAN, OF DETROIT, MICHIGAN, ASSIGNOR OF ONE-HALF TO
MAX C. KOCH, OF SAME PLACE.

CASH-CARRIER.

SPECIFICATION forming part of Letters Patent No. 425,007, dated April 8, 1890.

Application filed October 22, 1889. Serial No. 327,761. (No model.)

To all whom it may concern:

Be it known that I, WILLIAM S. SOLOMAN, a citizen of the United States, residing at Detroit, county of Wayne, State of Michigan, have invented a certain new and useful Improvement in Cash-Carriers; and I declare the following to be a full, clear, and exact description of the invention, such as will enable others skilled in the art to which it appertains to make and use the same, reference being had to the accompanying drawings, which form a part of this specification.

My invention has for its object certain new and useful improvements in cash-carrier apparatus, my purpose being to provide an apparatus of simple and economical construction and operation and of superior utility.

I accomplish my object as more fully hereinafter described, pointed out in the claims, and illustrated in the accompanying drawings, in which—

Figure 1 is a side elevation illustrating my invention. Fig. 2 is a plan view of the pawl-carrying slide, its track, stop, and a portion of the carrier, the wheel-supporting arm of the carrier being shown in section. Fig. 3 is a detail perspective view of a portion of the carriage, the carriage-supporting arms, the shaft to which the carriage is secured, and the sliding head. Fig. 4 is a vertical cross-section on the line $y-y$, Fig. 2. Fig. 5 illustrates a modification of my invention in side elevation. Fig. 6 illustrates a modification of the track-supporting bracket.

I carry out my invention as follows: A represents any suitable bracket, upon which various parts of the apparatus are supported and attached, as hereinafter described, and which is engaged upon any desired support A'. B is the track, engaged at its extremity to said bracket in any proper manner.

C represents the traveling carriage provided with wheels C' C², supported upon said track and journaled upon arms C³ of said carriage.

D denotes a reciprocatory catch or pawl pivotally engaged upon a slidable frame or bed D', said bed arranged to travel back and forth upon ways E E', engaged upon the bracket A at one extremity and upon a supporting-arm F at the opposite extremity. Said arm is

preferably attached to said bracket also, as shown.

G is an operating-lever fulcrumed upon the arm F, as shown at f, and is connected to the bed or frame D' to throw it in the desired direction upon the ways E E'.

H is a stop to limit the throw of the upper end of the operating-lever. Said lever may have engagement with the bed D' by means of an intermediate connecting-rod G', or the bed D' may be provided with a rack-bar and the upper end of the lever G be toothed, as shown in Fig. 5, to mesh therewith.

The carriage C is provided with a shaft I, having a fixed engagement in connection therewith. I' is a spring engaged upon said shaft intermediate the arms C³ of the carriage to retract and impel the carriage upon the track. The shaft is provided with suitable shoulders i at either extremity or otherwise properly constructed for engagement by the catch or pawl D, as shown. Sleeved upon the shaft toward the extremities of the carriage I also locate sliding heads J J', each constructed with wings j j' to abut against the outer end 75 of the ways E E' at either end of the track. The outer end of said ways may be provided with a curved connecting-bar e. The sliding heads are located on the inside of the arms C³, respectively, as shown.

The pawl D is provided with a spring d to hold it in normal position, so that it will firmly maintain its hold upon the shaft I until properly released therefrom.

Upon the ways E E', I locate a tripping-bar K, which is constructed with a wedge-shaped under face, as shown in dotted lines, Fig. 1, the construction and arrangement being such that when the adjacent end of the pawl or latch D is forced into engagement therewith 90 said end will be depressed, thereby lifting the forward end of the latch out of engagement with the shaft I.

The operation of the device is as follows: The carriage being at either end of the track, 95 the pawl engages the end of the shaft I, as shown in Fig. 1. The end of the shaft is constructed on an incline to permit the spring-controlled pawl to ride over the shoulder of the spindle and lock thereupon. In this po- 100

sition the wings j, j' of the sliding head adjacent to the ways $E E'$ abut against said ways and are thus prevented from moving farther in that direction. The arms C^3 of the carriage being rigidly engaged with the shaft, it will be seen that by seizing the lever G and forcing it in the proper direction the sliding frame or bed D , with the pawl, is forced toward the bar, carrying with it the shaft and the carriage. The sliding head adjacent to the ways $E E'$ is held from moving; but the opposite head, by the movement of the shaft and carriage, is moved forward therewith, thereby compressing the spring I until the end of the pawl is forced sufficiently under the tripping-bar K to liberate the pawl from the shaft, when instantly the spring impels the carriage to the opposite end of the track, where it is secured and operated in a similar manner.

20 In Fig. 6 I have shown the bracket A constructed for attachment to the ceiling instead of to a side wall, and in this case the auxiliary bracket A^2 , to which the ways $E E'$ are connected, may be adjustably engaged with the main bracket A , an arm A^3 being sleeved into an arm A^4 of the main bracket and being held in any desired point of adjustment by a set-screw A^5 . In this way an adjustable bracket is provided; but any other means of adjustment may be employed within the scope of my invention.

What I claim as my invention is—

25 1. In a cash-carrier apparatus, the combination, with supporting-ways, of a recipro-

catory pawl, a sliding carriage provided with a fixed shaft, sliding heads upon said shaft, a spring bearing on said heads, and means for disengaging said pawl from said shaft, substantially as set forth.

2. In a cash-carrier apparatus, the combination, with the supporting-ways $B E E'$, of a carriage mounted to slide upon the supporting-way B , a shaft fixed to said carriage, sliding heads sleeved upon said shaft and having projecting arms, a spring bearing on said heads, a pawl or catch supported upon the ways $E E'$ to engage said shaft, means for reciprocating said pawl and means for disengaging it from said shaft, and a stop secured to said ways $E E'$ for the ends of the projecting arms of the sliding heads to bear against, substantially as set forth.

3. In a cash-carrier apparatus, the combination, with the supporting-ways and the track, of a carrier mounted upon the track, a shaft fixed to said carriage, sliding heads engaged with said shaft, a spring bearing with its ends against the inner ends of said heads, a pawl mounted to slide upon the supporting-ways to engage the end of said shaft, and means for sliding the pawl, substantially as set forth.

In testimony whereof I sign this specification in the presence of two witnesses.

WILLIAM S. SOLOMAN.
